EXOTHERMIC REACTION CHARGE

Charles A. Cadwell, Cleveland, Ohio, assignor to
The Electric Railway Improvement Company,
Cleveland, Ohio, a corporation of Ohio

Original application January 13, 1941, Serial No.
374,229. Divided and this application November 30, 1942, Serial No. 467,340

3 Claims. (Cl. 75—27)

In the use of exothermic reaction mixtures, and particularly in the use of mixtures such as are employed in the well known alumino-thermic reaction to produce molten metal, one of the problems encountered is the proper disposition of the charge in the crucible. For example, where it is desired to produce molten copper by such reaction, the charge may comprise aluminum powder admixed with copper oxide in addition to other minor ingredients. It is also necessary to provide an ignition powder on the upper or exposed surface of the charge whereby the latter may be readily set off. Once started, of course, the alumino-thermic reaction is quite rapid and may even become violent due to the large amount of heat given off.

However thoroughly the ingredients of the charge are intermixed previously to placement in the crucible, I have found there is a tendency for such ingredients to segregate, when simply poured into the latter, due to differences in shape and specific gravity of the particles, and unless this be controlled, the charge will not "fire" uniformly. This is particularly objectionable in the case of a small charge, as required for certain operations, such as cast welding the ends of bonds to steel rails where a definite, relatively limited quantity of highly molten copper is desired.

For this and analogous uses of the alumino-thermic reaction, I have found it desirable, as set forth in my prior Patent No. 2,229,045, dated January 21, 1941, to utilize an alumino-thermic reaction mixture in which instead of powdered aluminum a powdered copper-aluminum alloy is employed, the effect of which is to reduce the violence of the reaction when the charge is ignited. Also, as set forth in said prior patent, the charge is desirably made up in package or cartridge form, so that the precise amount required for a particular operation may be deposited in the crucible which forms an associated part of the mold employed bonding operation. Even where, as prescribed, such cartridge, following removal of the cap which closes one end, is quickly inverted into the crucible and then withdrawn, a certain amount of segregation is apt to occur, with the result that when ignited the charge may not react uniformly or in its entirety.

The object of the present invention, accordingly, is to provide an improved method of charging a crucible with material for producing molten metal by exothermic reaction whereby such material will be deposited in the crucible

in a condition which will conduce to a uniform and complete reaction. At the same time the convenience of having a material available in package or cartridge form is retained.

To the accomplishment of the foregoing and related objects, the invention, then, consists of the steps hereinafter fully described and particularly pointed out in the claims.

The annexed drawing and the following description set forth in detail certain steps embodying the invention, such disclosed steps constituting, however, but one of various ways in which the principle of the invention may be used.

In said annexed drawing:

Fig. 1 is a transverse sectional view of an apparatus for rail bonding, such apparatus including a mold and associated crucible for the production of molten metal by exothermic reaction;

Fig. 2 is a perspective view of a cartridge used in packaging the charge;

Fig. 3 is a central section of such cartridge showing disposition of its contents;

Fig. 4 is an elevational view of a crucible adapted for use in my improved method, such crucible being designed for pouring the resultant molten metal instead of discharging the same directly into an associated mold; and

Fig. 5 is a transverse section of such pouring crucible, the plane of the section being indicated by the line 5—5, Fig. 4.

Referring to the rail bonding apparatus illustrated in Fig. 1, this will be seen to comprise a suitable frame 1 (shown only in part) which is adapted to rest upon the top of the rail head 2 and support a graphite mold block 3. The lower portion of such block is desirably encased in a close fitting metal shell 4 through which passes a pin 5 whereby the block is pivotally mounted in a clevis 6. Such clevis is in turn supported in frame 1 by means of a bolt 7 which passes through a boss 8 on such frame, and a leaf spring 9 is attached to the frame by the same bolting means and is interposed between said clevis and mold to resiliently bear upon the face of the mold opposite its rail-engaging face. It will be understood that frame 1 includes clamping means which engage with the rail head and retain the frame against transverse movement relatively to such head, so that the result of the action of said spring 9 is to retain the mold block 3 in close fitting contact with the rail head.

The mold block which is of refractory material, preferably graphite, has a mold cavity 19 connected by way of a sprue passage 20 with the

lower end of the downwardly tapering crucible 21, in which the reaction charge presently to be described is placed. Preliminary to placement of the charge, the lower end of the crucible is closed by a cup-shaped gate 22 of metal or equivalent material which is destructible by the heat engendered by the reaction or contact with the gate of the resultant highly heated molten metal. Because of its shape such gate is substantially self-positioned in the bottom of the crucible.

Attached to the top of the block 3 in which crucible 21 is thus provided, is a cover 23, such attachment being preferably by means of a hinge 24 so that the cover may be tilted clear of the crucible when it is desired to have access to the latter. Such cover arches upwardly over the crucible and is provided with a vent opening 25 centrally thereof, and so coaxial with the crucible, and this opening is in turn surrounded by an upwardly extending slightly flared rim 26.

Rim 26 on the crucible cover is designed to receive and ensure proper placement of a cartridge 27 in which the charge of reaction materials is packaged. As better shown in Figs. 2 and 3, this cartridge comprises a cylindrical container, e. g. of cardboard, permanently closed at one end as by a cap 28 and having a removable cap 29 at its other end. In filling such cartridge the required amount of igniting powder 30 is first placed therein and then the cartridge is filled with the main body 31 of the charge, such as the previously described mixture of comminuted copper oxide and copper-aluminum alloy in proper proportions. In utilizing the cartridge 27 just described, to charge the crucible in the apparatus illustrated in Fig. 1, the cap 29 is removed and the cartridge is placed in an inverted position in the upper rimmed portion of the cover 23, as illustrated in dotted cutline in Fig. 1. The open end of the cartridge is thus seated directly over the central opening 25 which communicates through the cover with the interior of the crucible.

As a result the contents of the cartridge will be centrally discharged in the form of a cylindrical stream against the bottom of the crucible chamber and then pile up and expand against the crucible wall by a shearing and rolling action of the particles which produces a filling with the finer particles and dust predominating along the axis of the crucible and the coarser particles against the wall. The upper surface of the charge 32, as thus placed in the crucible will be slightly mounded, as shown in Fig. 1.

The ignition powder originally in the bottom of the cartridge will now be on top of the charge in the crucible, properly disposed to be ignited. This may be done by dropping a match through the opening 25 following removal of the empty cartridge or by means of a spark gun discharged through such opening.

Upon ignition, the center of the fiery crater accompanying the reaction follows down the center column of finer particles which react more slowly than the coarser grains and by so doing give the latter time to roll into the fire, all to the end that upon completion of the reaction when the break through takes place, the metal is discharged as a hot shot rather than as a stream which may under the most adverse circumstances be a trickling stream.

It is readily seen that charging the crucible by pouring of the contents from an oblique position of the cartridge may result in a reaction crater that descends along a tortuous path, perhaps

undermining some of overlying materials and causing an eruptive spatter; the worst result of such a charge is, however, in the nature of the discharge of the hot metal—whether a shot producing an ideal weld or a slow stream piling up cold shot metal against rail or bond.

The molten metal produced by the exothermic reaction of the charge will melt the gate 22 instantly upon coming in contact therewith, and dropping downwardly through sprue opening 20 will collect in the mold cavity 19 in which the terminal portion 32 of the bond which is to be welded to the rail head 2 is held in proper position by means of gripper fingers 33. The result is that the strands composing the bond terminal are more or less interfused into a solid molded bond head which is attached to the rail with a high degree of permanence.

In the modified construction illustrated in Figs. 4 and 5, the crucible 34 is provided with a pouring lip 35 instead of with a sprue opening, and a handle 36 is attached thereto by means of a clamping ring 37. The charging cover 38, which is similar in form with that previously described, is hinged to the crucible on the side toward the handle, and a spring catch 39 is provided on the latter to engage and retain the cover in open position when pouring molten metal from the crucible. This form of crucible is particularly adapted for use in the production of relatively large charges of molten metal produced by exothermic reaction, the metal then being poured into one or more molds in conventional manner.

The various features of construction which characterize my improved crucible, of which several forms are herein illustrated and described, forms the subject matter of my co-pending application filed January 13, 1941, Serial No. 374,229, out of which the present application has been divided.

Other modes of applying the principle of my invention may be employed instead of the one explained, change being made as regards the method herein disclosed, provided the step or steps stated by any of the following claims or the equivalent of such stated step or steps be employed.

I therefore particularly point out and distinctly claim as my invention:

1. In a method of charging a crucible with material for producing molten metal by exothermic reaction, such material comprising a mixture of ingredients comminuted to different degrees of fineness, the steps which consist in permitting a measured body of such material to flow freely by gravity through an opening restricted in area relatively to the cross section of such crucible and located approximately centrally over such crucible, whereby such material is deposited in the form of a symmetrical, mounded mass wherein the component ingredients are distributed uniformly in successive descending planes and then similarly placing on the mounded top of such body a smaller body of ignition powder.

2. In a method of charging a crucible with material for producing molten metal by exothermic reaction, such material comprising a mixture of ingredients comminuted to different degrees of fineness, the steps which consist in pouring a measured body of such material into such crucible from above, and restricting the flow of such body where it enters the crucible to an area substantially less than the cross-section of such crucible and located approximately centrally with

respect to the latter, whereby such material is deposited in the form of a symmetrical, mounded mass wherein the component ingredients are distributed uniformly in successive descending planes.

3. In a method of charging a crucible with material for producing molten metal by exothermic reaction, such material comprising a mixture of ingredients comminuted to different degrees of fineness, the steps which consist in pouring a measured body of such material into such crucible from above, and restricting the flow of such

body where it enters the crucible to an area substantially less than the cross-section of such crucible and located approximately centrally with respect to the latter, whereby such material is deposited in the form of a symmetrical, mounded mass wherein the component ingredients are distributed uniformly in successive descending planes, and then similarly discharging on the mounded top of such body a smaller body of ignition powder.

CHARLES A. CADWELL.
